US00D627596S

(12) **United States Design Patent**
Hillebrenner et al.

(10) **Patent No.:** **US D627,596 S**
(45) **Date of Patent:** **** Nov. 23, 2010**

(54) **CUP**

(75) Inventors: **William Hillebrenner**, Chicago, IL (US); **Weston Koennecke**, Oak Park, IL (US)

(73) Assignee: **Solo Cup Operating Corporation**, Lake Forest, IL (US)

(**) Term: **14 Years**

(21) Appl. No.: **29/320,143**

(22) Filed: **Jun. 20, 2008**

Related U.S. Application Data

(63) Continuation of application No. 29/320,019, filed on Jun. 18, 2008.

(51) **LOC (9) Cl.** **07-01**

(52) **U.S. Cl.** **D7/396.2; D7/509; D7/527**

(58) **Field of Classification Search** ..... **D7/396.4, D7/396.2, 387, 392.1, 523, 509, 624.1, 532; D5/7, 99; D9/516, 549, 551; 428/34.4; 229/400; 215/387, 382, DIG. 7; 220/703, 592.16, 220/592.17; 65/69**

See application file for complete search history.

(57) **CLAIM**

The ornamental design for a cup, as shown and described.

DESCRIPTION

FIG. 1 is a perspective view showing a first embodiment of our new design of a cup;

FIG. 2 is a front view thereof;

FIG. 3 is a top view thereof;

FIG. 4 is a side view thereof;

FIG. 5 is a bottom view thereof;

FIG. 6 is a perspective view showing a second embodiment of our new design of a cup;

FIG. 7 is a front view thereof;

FIG. 8 is top view thereof;

FIG. 9 is a side view thereof;

FIG. 10 is a bottom view thereof;

FIG. 11 is a perspective view showing a third embodiment of our new design of a cup;

FIG. 12 is a front view thereof;

FIG. 13 is a top view thereof;

FIG. 14 is a side view thereof; and,

FIG. 15 is a bottom view thereof.

The dash-dot-dash broken lines shown in the drawings represent unclaimed boundaries of the claimed design.

The broken lines represent portions of the design that form no part of the claim.
